UNITED STATES PATENT OFFICE.

BENJAMIN K. READ, OF DETROIT, MICHIGAN, ASSIGNOR TO HARRY W. BEGGS, OF VINCENNES, INDIANA.

SWITCH.

1,302,089.

Specification of Letters Patent. Patented Apr. 29, 1919.

Application filed June 26, 1916. Serial No. 105,883.

To all whom it may concern:

Be it known that I, BENJAMIN K. READ, a citizen of the United States, and residing at Detroit, in the county of Wayne and State 5 of Michigan, have invented a new and Improved Switch, of which the following is a specification.

This invention relates to means for changing electric circuits at the reversal of movement of revoluble shafts and its object is 10 to provide a switch which may be constructed at low cost, which will be effective and which will not get out of order.

This invention consists, in combination 15 with a series of contacts, of a plate movable over said contacts, a shaft adapted to revolve in both directions, and novel means operated by said shaft to swing the plate so as to disengage one contact and engage another at the reversal of movement of said shaft. It further consists in 20 so mounting a driving member on said shaft that it will frictionally transmit movement to said plate at the beginning of the reversed movement 25 of said shaft.

In the accompanying drawing, Figure 1 is a plan of my improved switch. Fig. 2 is a section on the line 2—2 of Fig. 1. Fig. 3 is a section through one of the operating 30 links.

Similar reference characters refer to like parts throughout the several views.

Any desired form of base 1 supports the 35 posts 2, 3 and 4, each having a contact plate 5 preferably provided with a slight projection 6. Adjacent these contacts is a post 7, preferably provided with an enlarged eccentric lower end 8 that is held in a proper socket in a lower portion 9 of the base 1 by 40 means of a washer 10.

Revoluble on the post is a collar 12 of insulating material which carries a contact plate 13, preferably of spring brass and provided with a slit 14 to insure greater 45 resilience. A collar 15 and a block 16 of metal are also revoluble on this post, being positioned between the shoulder 17 and the washer 18 that is held in position by the screw 19. The collar 12 is secured to the 50 metal collar 15 and block 16.

Slidable between the collar 15 and washer 18 is a lever 21 having a slot 22 into which the block 16 extends. A shaft 23 that is 55 revolved in any desired manner has rigidly secured to it a stepped collar 24 having an

enlarged portion 25 on which the ring 26 is revoluble. Another collar 27 has a shoulder 28 that rests on the inner end of the lever 21 which is pivoted to the ring 26 by means of a screw 30. The collar 27 is slidably 60 vertically on the shaft and on the key 31 and rests on the lever 21, pressing it and the ring 26 against the collar 24 and producing sufficient friction to turn this ring as far as permitted by the lever. 65

While the shaft is turning in the direction of the arrow 33, the lever and the plate 13 will be held in the position shown in solid lines in Fig. 1. But when the direction of revolution of this shaft is reversed, the 70 screw 30 will be carried around toward the left, the lever will slide on the block 16 and the collars 12 and 15 and plate 13 will be turned until the parts reach the positions shown in dotted lines in Fig. 1. 75

The width of the plate 13 will determine how long it engages the contact 5 connected to the post 4 after this plate engages the contact connected to the post 2. It is easily seen that when this plate is narrower, the engagement of the plate with one of the outside contacts may cease before engagement with the other begins. The drawing shows two sets of circuit changing devices, but it is evident that one of these sets may be omitted or that 80 additional sets may be installed. The details of construction and proportions of parts may all be changed without departing from the spirit of my invention. 85

I claim:—

1. In a switch, the combination of a shaft 90 adapted to revolve in either direction, a ring carried by the shaft, means carried by the shaft to support and frictionally engage the ring and turn it in either direction, a series 95 of contacts, a pivotally mounted plate adapted to engage said contacts, and means connected to said ring to swing said plate across said contacts.

2. In a switch, the combination of a driving member revoluble in either direction, a ring loosely mounted thereon and adapted to be carried around by the friction between it and said driving member, a series of contacts, a plate which is movable across said contacts, and means connecting the plate to the ring whereby the ring may actuate the plate. 100

3. In a switch, the combination of a shaft adapted to revolve in either direction, a pair 105 of collars on the shaft, one being rigidly 110

secured to the shaft and the other revoluble therewith but slidable thereon, a ring supported by one collar, a series of contacts, a supporting post, a collar of insulating material revolvably mounted thereon, a plate carried by the collar and engaging the contacts, and a lever connected to the collar of insulating material and to said ring whereby said plate may be moved when the shaft 10 reverses its direction and swings the lever.

4. In a switch, the combination of a shaft adapted to revolve in either direction, a ring concentric with the shaft, means connected to the shaft to support the ring and to frictionally drive the same in the direction of movement of the shaft, a base, a post mounted in said base, a collar revolvable on said post and having a narrowed extension, a

lever having a slot into which said extension projects so that said lever may swing said 20 collar, a pin connecting one end of said lever to said ring, a contact plate carried by the collar, and a series of contacts adapted to be bridged by said plate.

5. In a switch, the combination of a driving member adapted to turn in either direction, a ring supported by said driving member and turned by the friction between them, a weight adapted to press the ring against the driving member, a pair of contacts, a 30 plate which is movable from one contact to the other, and means connecting the plate to the ring whereby the ring may actuate the plate.
